UNITED STATES PATENT OFFICE.

AUGUST R. SCHOENKY, OF SOMERVILLE, MASSACHUSETTS, ASSIGNOR TO REECE SHOE MACHINERY COMPANY, OF BOSTON, MASSACHUSETTS, A CORPORATION OF MAINE.

ROUNDING MACHINE.

Application filed August 28, 1919. Serial No. 320,382.

To all whom it may concern:

Be it known that I, AUGUST R. SCHOENKY, a citizen of the United States, residing at Somerville, in the county of Middlesex and 5 State of Massachusetts, have invented a new and useful Rounding Machine, of which the following is a specification, reference being had therein to the accompanying drawing.

Rounding machines, used in the manufacture of boots or shoes, are employed for preliminarily trimming or rounding the extending edges of the soles preparatory to the final sole stitching operation. For example, 10 with a welt shoe the outsole may be temporarily attached to the connected insole, welt, and upper, while the latter is occupied by the wooden last, and at this stage the trimming or rounding of the outward extension, consisting of outsole and welt, to the approximate or final contour, is performed on the rounding machine. While the present invention may be applied to various types or 15 classes of rounding machine, I select for illustration that shown in my prior Patents, No. 1,040,433 of October 8, 1912, and No. 1,243,228 of October 16, 1917. In the class of rounder shown in said patents, certain 20 principal elements or instruments are shown which are substantially duplicated in the present illustration of my invention, and a recital of which will establish the characteristics of the illustrative class of rounding machine. The rounding or trimming is performed by a cutter C, this being a constantly 25 moving blade preferably vibrated rapidly with its carrying arm so as to deliver chopping or cutting strokes against the work. The work progressively advancing by steps shorter than the width of the cutter, a continuous trim line is produced. The feed of 30 the work is performed by opposing work clamping members which clamp the work, shift transversely, release the work, and return. The rear work clamp member is a 35 freely rotatable roller or cylinder B. This is pressed forcibly but yieldingly forward against the work and is usually retractable rearwardly by a pedal to permit the insertion or removal of the work. The opposed or 40 front work clamping or feeding member D is given a movement to and from the work for clamping and unclamping it against the rotatable clamp or work rest B. The co-operating clamping members B and D have a 45 combined movement along the line of feed,

that is, transversely, so as to permit the 4-motion movement described. Usually the cutter vibrates forwardly and backwardly and the work is fed transversely or horizontally, for example, leftwardly through the 60 path of the cutter. The work is held up in position by the operative, who is able to observe the progress of the rounding. Work guiding means is employed in the form of one or more guides above the path of the 65 work, so that the operative is not required to use his judgment but merely holds the work firmly up against the guide as it feeds and is trimmed. The work is frequently guided in two ways and by two separate guides, 70 either of which may be put into effect. In trimming along the shanks of a shoe, it is desirable to guide the shoe from the crease, that is, the angle between the upper and sole. A crease guide E is therefore used, and this 75 is shown to be stationary. Between feeding movements the work is held against this guide. In trimming around the fore part of the shoe it is preferable to guide according to the contour of the last, and a last guide F 80 is shown adapted to contact the shoe upper outside the wooden last. The crease guide being stationary, the last guide will be shiftable from an elevated inoperative position to a lowered operative position, in which 85 latter it engages the shoe and depresses it so as to assume the guiding function which is thus taken from the crease guide. Other instruments may be used. For example, the prior patents show a knife H for cutting a 90 channel at the under side of the outsole to facilitate the subsequent outsole stitching. This channeling knife moves with the work, clamping, or feeding devices, advancing with the shoe and operating on the return 95 stroke while the shoe is stationary. A welt guttering tool G, moved into position when the last guide is in operation, serves to form a slight depression or gutter at the top of the welt opposite the channel in the outsole, 100 to receive the visible portion of the stitches around the fore part of the shoe.

The main object of the present invention is to afford an improved mechanism for causing the width of the extending edge of the 105 sole to be varied around the contour of the shoe. The expired patent of French & Meyer, No. 630,339, patented August 8, 1899, shows a cam mechanism for this purpose, and in part this invention is an improvement there- 110

over. The cutter or the work guide, preferably the latter, is fitted in such manner as to enable the position or relation of the two to be varied during the rounding operation. 5 This may be applied to any kind of work guide; the width of the extension may be varied when guiding from the crease or when guiding from the last. The variation in extension at the fore part of the shoe, 10 however, is the more important purpose of the present invention which, therefore, will be shown herein as applied merely to the fore part of the guide, that is, the last guide F. Specifically, the desired end is attained 15 by providing means for varying the height of the work guide during the rounding operations. Uniformity of shape and style is secured by definitely controlling the stated operation by means of a controller or cam 20 which works automatically and varies in a predetermined manner the relation between the work guide and cutter; specifically, it varies the height of the work guide and, therefore, the path of the shoe relatively to 25 the path of the vibrating cutter.

A further object is to render the shape-control, stated in the preceding paragraph, adaptable or adjustable for different sizes of shoes. Where the feed and cut length 30 are not proportioned to the size of the shoe, the number of cuts or cycles will be greater with a large than a small shoe. The controller or cam if set for one size would not give a corresponding control for another 35 size, unless adjusted. This object is accomplished herein by providing a control or cam mechanism which has its action or progress adjustable at will so that it may be initially set to correspond to the size or 40 contour-length of the shoe being rounded. Specifically I herein show a slow moving control cam, the rate of advance of which is adjusted, being rendered more rapid for small and more slow for large shoes, proportionately, so that precisely the predetermined shape or style will be correspondingly produced on all sizes of shoes. 45

A further object is to enable the shape control to be reversed in action, so that the operative may first round a right shoe and then a left shoe. This is advantageous in order that shoes may be manufactured in pairs. If the rounding of the right shoe is begun at the outside shank, the rounding 55 of the left shoe will be begun at the inside shank, and this reversibility of control will insure both shoes having precisely corresponding shape. This object is herein attained by providing that the controller or cam is actually reversible in its action or progress. Specifically it is herein shown automatically reversed so that it travels in one direction for the one shoe and in the reverse direction for the succeeding shoe. 60 65 It advances to the end of its travel and on

the next rounding operation starts back over the same course.

Further objects are to improve and render more convenient and efficient the rounding machine, in various respects, especially 70 to render complete and practical each of the previously above recited features, and to adapt them more especially to the particular class of rounding machine shown in the prior patents mentioned. These objects 75 are attained by the features of combination, arrangement, mechanism and detail herein illustrated, described or claimed.

In the accompanying drawings, Figure 1 is a front elevation of a rounding machine, 80 which for illustrative purposes is of the class shown in said prior patents, embodying the several features of the present invention.

Figure 2 is a left elevation of said machine, the last guide F being in elevated or inoperative position.

Figure 3 is similar to Figure 2 with, however, the last guide in its operative position. 90

Figure 4 is a left elevation of the eccentric and adjusting devices for altering the speed of the controlling slow cam, shown partly in section on the line 4, 4 of Figure 5.

Figure 5 is a central section on the line 95 5, 5 of Figure 4.

Figure 6 is a face view of the controller cam.

Figure 7 shows the trimmed shoe, diagrammatically marked to indicate the operations performed. 100

Figure 8 shows the shoe in cross section before the trimming or rounding operation.

It is not deemed necessary to describe in detail the various features which are already 105 made clear in the prior patents. The parts having to do with the objects and features of the present invention will now be described.

At the top of a vertical post 9 is the 110 machine head 10. Control pedal or pedals may be at the base of the post. The main or power shaft 11 extends horizontally and transversely through the head. From left to right, the main shaft carries the following elements. The belt pulley 12 is at the 115 left extremity. An eccentric 13 is shown which causes the advance, in a step-by-step manner, of the slow cam or controller to be described. The shaft is next formed with 120 a first crank and a second crank 15, and beyond that is a shaft cam 16. The use of the two cranks is in accordance with my prior Patent 1,243,228, in which is explained how, with the use of these cranks 125 and the link and lever mechanism operated thereby, a machine of greater smoothness, quietness and speed is attained. The first crank serves to give the feeding movements to the work feeding devices. The crank 130

operates the cutter C. The cam 16 moves the front clamp or work feed member D to and from the work.

The present invention has to do more particularly with the last guide F. Already I have mentioned its movements between the upper or inoperative, and lower or operative positions; and when in its operative position it has slight variations of position 10 relatively to the path of the cutter so as to vary the extension or width of the outstanding shoe sole. A convenient way to fit the last guide for such movements and adjustments is through a carrying arm 20 15 which swings with its carrying shaft 21, somewhat as in the prior patents. Mounted on the short shaft 21 is a rearwardly extending arm 22 provided with an upwardly directed forked end 23. The carrier or arm 20 20 is constantly acted upon by a spring 24 tending to raise it to inoperative position.

The last guide and carrier may be pulled down against resistance of spring 24 by any suitable automatic or non-automatic means, 25 such as the pedal connection 27 extending to a convenient pedal which may be depressed at will to bring the guide down to its operative position. The means for limiting, varying and controlling the downward 30 or operative position of the guide by slow moving cam 105 will be later explained.

The slow traveling controller or cam 105 which dominates the operation of the present invention, may be advanced in a step-by-step manner by the action of the eccentric 13 of the main shaft 11, by the following connections. The eccentric is surrounded by the usual ring or strap 31, the arm or rod 32 of which extends upwardly 40 to where it bears laterally against a fixed frame part 33. This frame part has a somewhat elongated guiding slot or recess 34 to receive a roller 35 mounted on the eccentric rod. This permits the up-and-down rod 45 movements, and is also sufficiently wide to permit the rod to swing slightly forwardly and rearwardly. A spring 37 constantly pulls the eccentric rod forwardly to the position illustrated in Fig. 3, away from 50 the rear side of slot 34.

The up-and-down eccentric rod movements operate through a pawl 38 mounted on it to advance slowly and step-by-step a toothed wheel 40. It will be perceived that 55 this causes a slow clockwise travel of the disk or ratchet wheel and, as will be explained, this drives the control cam 105 in the proper direction for rounding a right shoe. At this point I also mention that a second or upper pawl 39 is provided on the eccentric rod, this co-operating with a second toothed disk or ratchet wheel 41 for the purpose of driving counterclockwise during the rounding of the left shoe. It is intended 60 that one or the other of the pawls 38 and 39

shall be in operative position. Alternately, they will be thrown out of operation. The two pawls are accommodated in a recess formed in the eccentric rod and are provided with outstanding pins or studs 42 and 43, respectively, through which they or either of them may be thrown away from the toothed disk to render the same inoperative. The pawls are shown spring-pressed toward operative position. 75

The two toothed disks 40, 41, through which the eccentric movements secure controller action in one direction or the other, are keyed to a cross shaft 50 which may be termed a controller shaft or cam shaft, as 80 it carries or drives the slow moving control cam 105.

The speed of action or travel of the controller shaft 50 and the cam 105 may be regulated in accordance with this invention, for the purpose of adapting the machine to shoes of varying sizes, by suitable mechanism such as the following. This preferably operates by changing the throw of the eccentric 13. The power shaft 11 is 90 shown as having flattened side portions 53 for engaging the corresponding sides of a recess 54 formed in the eccentric. These fittings enable the eccentric to be radially shifted to change its throw. The change 95 may be effected and the eccentric held in any adjustment through a pair of radial pins 55, 55 extending inwardly from the eccentric through holes in the shaft. The shaft at this point is hollow, and within it 100 is provided a cam 57 secured at the end of a sliding rod 58 movable axially within the hollow of the shaft, and compelled to turn with the shaft by a stud 59 passing through the shaft wall and engaging a keyway in 105 the rod 58. Axial movements of the rod cause the cam 57 to act upon the rods 55 and shift the eccentric radially to afford the desired eccentricity.

Such adjustment may be effected through 110 a grooved collar 60 at the extreme or left extremity of the interior rod 58. This collar 60 is shown engaged by a yoked arm 61 fulcrumed at 62 and having an operating extension 63. A right-threaded rod 64 is 115 pivoted to the extension 63, and in line with it is a left-threaded rod 65 pivoted to a frame part. A wheel or nut 67, properly 120 inferiorly threaded, engages both the threaded rods 64 and 65 so that when the wheel is turned this swings the yoked lever 61 and thereby causes adjustment of eccentric throw.

The wheel 67 may be turned to any desired position. It is shown as provided with 125 a number of peripheral teeth or notches, corresponding roughly with the number of shoe sizes to be rounded, and on each of these teeth is marked an indication of the size of the shoe to be rounded when the 130

wheel is set with such marking opposite an opening or window in a bracket 68.

A tensioned coil spring 69 returns the adjusting wheel 67 always to its extreme 5 or zero position when released, and serves to maintain it in proper position, engaging the following described setting means.

A collar 71 is mounted loosely on the wheel 67, and from this collar extends forwardly a handle 72 within convenient access. A pawl 73 is connected to the handle and is spring-pressed into engagement with the peripheral teeth of the wheel. The handle 72 may be moved up-and-down between upper and lower stops 74 and 75. A spring 76 lifts it to its highest position. When the handle is depressed, it throws downward the front side of the wheel. The wheel may there be held by a supplemental 20 pawl 77 pivoted to permit its removal from operative position. When the handle 72 rises, the pawl 73 passes over one tooth of the wheel. In this way the operator may readily shift the wheel to bring about the 25 desired adjustment, according to the size of the shoe to be rounded. On the handle is shown an unlatching lever 79 which, when pressed, withdraws the pawl 73. By lifting at the same time the pawl 77, the spring 30 69 will rotate the index wheel 67 to its zero or extreme position.

Rather than have the operative effect a manual adjustment to reverse the direction of travel of the controller 105 for right and 35 left shoes, alternately, this is herein performed automatically, for example by the following mechanism. Mounted loosely on the controller shaft 50 is a pawl-changing disk or cam 81. This has alternate elevations 82 and recesses 83 around its periphery. These co-operate with the studs 42 and 43 on the pawls 38 and 39. The studs and the elevations on the disks are so spaced that, while an elevation holds one pawl re- 45 tracted, the stud of the other pawl is in the recess beneath the elevations, rendering its pawl operative. Thus, in Fig. 3 the lower pawl is operative, while the upper one is held away from its toothed disk.

50 In order to automatically shift the pawl-changing disk 81 after each rounding operation, I have shown, connected to the disk, a toothed wheel 85 having one tooth for each elevation and one for each depression on the disk. The wheel 85 is acted upon by a spring-lifted pawl 86 which is mounted on a long rearwardly-extending slide bar 87 having a stud 88 engaging in the fork 23 of the arm 22 which swings with the last 55 guide carrier 20. The result is that when the last guide has performed its service on each shoe and rises, this shifts the pawl-changing disk, as described.

The advance of shaft 50 and the controller 105 thereon may be caused to cease

or suspend while the last guide is inactive. To give this result the slide bar 87 is provided with a cam 89, which, as the guide rises, depresses the rear arm 90 of a bell crank the upward arm 91 of which is connected by link 92 to the upper end of the eccentric rod 32, so that the rod and its pawls 38, 39 are shifted to the inoperative position shown in Fig. 2.

A hand wheel 93 mounted at the right end 75 of controller shaft 50, permits manual shifting or adjustment of the shaft and the controller 105, to modify or correct the position or timing of these parts.

The last guide carrier arm 20 is shown as 80 having an upward extension 100. In the prior patents the upper extremity of this was formed as a stop which came forwardly with the descent of the guide and met a fixed abutment or stop, giving the guide always 85 the same uniform operative position. In the present machine, the upward extension or stop member 100 is formed with an enlarged head 101 interiorly engaged by the threaded stop bolt 102 which is therefore 90 adjustable in position, and is secured in any adjustment by lock nuts 103. The forward end of the stop bolt 102 is provided with a cam roll 104, and this engages directly against the slow moving controller or cam 95 105 which is mounted on, so as to rotate with, the controller shaft 50.

By this arrangement, the forward swing of the head 101, and therefore the downward swing of the guide, is limited or controlled 100 according to the contour of the cam. When the shoe is being guided by the last, the roller 104 rides on the cam 105. Slight elevations in the cam will slightly lift the guide and therefore slightly lift the shoe, and produce a narrower sole extension at that point. Depressions in the cam produce greater width in the extension. In order, therefore, to slightly vary the height of the guide, that is, its relation to the path of the cutter, during a rounding operation, to secure any desired contour of shoe sole, it is only necessary to correspondingly form the contour of the controller or cam 105.

The controller is shown in Figs. 2, 3 and 6 115 as having such contour as to produce a shoe substantially such as is shown in Fig. 7. The diagram numbers from 1 to 20, and 21 correspond with 1, indicate the cam contour and its effect. At each point the sole extension corresponds with the cam radius.

It will thus be seen that I have described a rounding machine embodying the principles and attaining the advantages of the present invention. Obviously, many matters of combination, arrangement, structure, mechanism, and detail, may be variously modified without departing from the underlying principles, and therefore it is not intended to limit the invention to such mat- 125 130

ters except in so far as specified in the appended claims.

What is claimed is:

1. A shoe rounding machine comprising means for feeding the work, a trimming cutter and a guide against which the shoe contacts during operation, the elements, cutter and guide being relatively adjustable during operation to vary the width of the sole extension around the shoe, characterized by a controller 105 progressively shiftable to vary the position of one of said elements, the same at its travel end being reversible in direction to change for right or left shoes, a pawl and ratchet device for advancing the controller having two pawls acting in opposite directions, a pawl control cam actuated by the guide's retraction after one shoe is completed and operating to throw one pawl out of action and the other into action, and pawl vibrating means.
2. A shoe rounding machine comprising means for feeding the work, a trimming cutter and a guide against which the shoe con-

tacts during operation, the elements, cutter and guide being relatively adjustable during operation to vary the width of the sole extension around the shoe, characterized by a controller 105 progressively shiftable to vary the position of one of said elements, the same at its travel end being reversible in direction to change for right or left shoes, a pawl and ratchet device for advancing the controller having two pawls acting in opposite directions, a pawl control cam actuated by the guide's retraction after one shoe is completed and operating to throw one pawl out of action and the other into action, and pawl vibrating means.

In testimony whereof, I have affixed my signature hereto.

AUGUST R. SCHOENKY.
